LIQUID DISPENSER

Filed Sept. 7, 1929

Milton L. Baker Inventor

Lyons & Lyons ^{By} Attorneys

UNITED STATES PATENT OFFICE

MILTON L. BAKER, OF SAN RAFAEL, CALIFORNIA, ASSIGNOR TO STANDARD OIL COMPANY OF CALIFORNIA, OF SAN FRANCISCO, CALIFORNIA, A CORPORATION OF DELAWARE

LIQUID DISPENSER

Application filed September 7, 1929. Serial No. 390,932.

This invention relates to liquid dispensers and, more especially, to that type of liquid dispenser having a pump secured to the cap of a container so that the pump parts are **5** movable and replaceable with the cap.

An object of the invention is the general improvement of liquid dispensers of this type.

The invention relates to liquid dispensers **10** of the type employed, for example, in the lubrication of more or less inaccessible parts of machinery, for example, where the lubricant is to be distributed over extended surfaces as is requisite in the lubricating of the **15** leaves of motor vehicles. In lubricating such inaccessible points as the spring leaves of motor vehicles, it is difficult to hold the container in a position insuring gravity flow of the lubricant from the container and, **20** besides, it is generally more convenient and practical to apply the lubricant from below the point that is to be lubricated, thus requiring that the lubricant be pumped from the container.

25 Accordingly, one of the objects of this invention is to make provision for applying a lubricant to comparatively inaccessible places regardless of the comparative elevations of the source of supply and point of application of the lubricant.

Another very important object of the invention is to insure proper support of that portion of the discharge tube that projects from the cap of the container.

35 Other objects and advantages will appear in the subjoined detailed description.

The accompanying drawings illustrate the invention.

40 Fig. 1 is a view, mainly in section, of a liquid dispenser constructed in accordance with the provisions of this invention, the pump being in place in the container.

Fig. 2 is a reduced view of the pump and the container cap to which it is secured.

45 Fig. 3 is an elevation of the container shown in Fig. 1, the neck thereof being shown in section and another cap being shown in place on said neck.

Referring to the drawings, a container or **50** can is indicated at 4 and is provided with a

neck 5 that may be closed by a cap 6, as in Fig. 3, or by a cap 7, as in Fig. 1. The dispenser is sold with both of said caps and, when sold, the cap 6 is in place to close the neck.

Connected with the cap 7 is a pump, indicated in general by the character 8 and constructed as follows: A vertical pump barrel 9 is fixed at its upper end to the inner face of the cap 7 and working in the barrel 9 is a plunger 10 operated by a plunger rod 11 **55** which projects through a small opening 12 in the cap 7. The outer end of the plunger rod 11 is provided with a knob 13 or other suitable handle by which the plunger rod is reciprocated for operation of the plunger. **60**

Within the barrel 9 is a shoulder 14 which limits upward movement of the plunger 10. Upward motion of the plunger 10 is produced by a coil spring 15 positioned within the barrel 9 between said plunger and the lower end of the barrel 9, said lower end being formed by a head 16. The head 16 is provided with a port 17 to communicate the interior of the barrel with the interior of the can 4 and said port is controlled by a ball check valve 18 which, being positioned above the port 17, is adapted to open upwardly and close downwardly. **70**

Communicating with the lower portion of the bore of the barrel 9 adjacent to the valve 18 is an L-shaped discharge tube comprising legs 19, 20 positioned substantially at a right angle to each other. The lower end of the leg 19 is secured to the barrel 9 and said leg projects through a small opening 21 in the cap 7. The tube 19 parallels the barrel 9 and, preferably, is positioned quite close to said barrel. **75**

The leg 20 is the longer of the two legs and it extends substantially at right angles to the longitudinal axis of the container 4. The leg 20 is adequately supported from the cap 7 by a stiffening member 22 which, in the present instance, is of tubular construction and encloses a portion of the discharge tube **80** 20. The stiffening member 22, in this instance, is tapered, the larger end being firmly soldered or otherwise secured in any suitable manner to the outer face of the cap 7 and, in this instance, to the top of said cap. The **85** **90** **95** **100**

smaller end of the stiffening member 22 is in contact with the discharge tube 20, and, in this instance, said smaller end substantially fits around the discharge tube. The stiffening member 22, extending both below and above the discharge tube 20, offers considerable resistance to upward and downward bending of the discharge tube.

Screwed or otherwise secured to the outer end of the discharge tube 20 is a nozzle 23 provided with a relatively small discharge orifice 24 so that the liquid dispensed will be ejected from the nozzle in a fine jet.

The invention hereinbefore described operates as follows: The container 4 closed by the cap 6 will be supplied to the customer together with the pump 8 mounted on or secured to the cap 7. The purchaser will remove the cap 6 from the neck of the container and substitute therefor the cap 7. In placing the cap 7 on the neck, he will first insert the barrel 9 in the container and then turn the leg 20 about the neck of the container so as to screw the cap down. The operator applies the nozzle 23 against or adjacent to the part to be lubricated and operates the plunger rod 11 in a manner well understood in the art relating to pumps of this character. Moving the plunger 10 against the pressure of the spring 15 forces liquid from the barrel through the discharge tube 19. The operator then allows the spring 15 to retract the plunger and the valve 18 then opens to admit liquid from the container into the barrel.

To make the cap 7 tight, it is preferable that a gasket 23 be employed.

I claim:

1. A pump construction comprising a cap adapted for closing the mouth of a container, a barrel secured at its upper end to the inner face of the cap, a plunger in the barrel, a rod connected with the plunger and projecting through the cap, a tubular member secured to the outer face of the cap and extending away from said cap approximately at a right angle to the axis of the pump barrel, and an L-shaped tube having one leg projecting through the cap and extending along side of the barrel and communicating with said barrel, the other leg of the L-shaped tube projecting through and supported by the said tubular member.

2. A pump construction comprising a cap adapted for closing the mouth of a container, a barrel secured at its upper end to the inner face of the cap, a plunger in the barrel, a rod connected with the plunger and projecting through the cap, a tapered tubular member secured at its larger end to the outer face of the cap and extending away from said cap approximately at a right angle to the axis of the pump barrel, and an L-shaped tube having one leg projecting through the cap and extending alongside of the barrel and

communicating with said barrel, the other leg of the L-shaped tube projecting through and fitting the smaller end of the tubular member and projecting horizontally beyond the outer end of said tubular member.

3. Apparatus for lubrication comprising, a container for lubricant, a cap for said container, a pump barrel attached to said cap and adapted to be submerged in lubricant when the cap is in place, a plunger in said pump barrel, a spring holding the plunger in raised position, a plunger rod extending through the cap and terminating in a handle, a tube leading from the pump barrel for the discharge of lubricant when the plunger rod is depressed, an extension to said tube extending a substantial distance at approximately right angles to the axis of the container, a reinforcement for said extension secured to the upper face of the cap and projecting approximately at a right angle to the axis of the pump barrel and beyond the side of the container to protect the tube against accidental damage and a nozzle of reduced bore for the end of said extension.

4. Apparatus for delivering lubricant comprising a container for said lubricant, a cap for said container, a pump barrel attached to said cap and adapted to be inserted within said container, a plunger in said pump barrel with a plunger rod extending through said cap, an L-shaped discharge tube from the pump barrel passing through said cap and extending a substantial distance beyond said cap, a stiffener for said tube attached to said cap and extending approximately at a right angle to the axis of the pump barrel and supporting the horizontal leg of said tube beyond said cap, and a delivery nozzle for said discharge tube.

5. Apparatus for delivering lubricant comprising a container for the lubricant provided with a threaded neck, a cap screwed onto said neck, a pump barrel attached to the cap and projecting into the container, a plunger in the pump barrel, a tubular stiffening member secured to the outer end of the cap and extending approximately at a right angle to the axis of the pump barrel, and an L-shaped discharge tube having a vertical leg connected with the lower end portion of the pump barrel, said tube provided with a leg extending at a right angle to the pump barrel through the tubular stiffening member, said last mentioned leg being supported beyond the side of the container by said tubular stiffening member.

Signed at San Francisco, Calif., this 26th day of August, 1929.

MILTON L. BAKER.
